UNITED STATES PATENT OFFICE

122,907

DESIGN FOR A GAME BOARD

Freeman R. Stearns, Ludington, Mich., assignor to Carron Industries, Inc., Ludington, Mich.

Application December 18, 1939, Serial No. 88,985

Term of patent 3½ years

To all whom it may concern:

Be it known that I, Freeman R. Stearns, a citizen of the United States, residing at Ludington, in the county of Mason and State of Michigan, have invented a new, original, and ornamental Design for a Game Board, of which the following is a specification, reference being had to the accompanying drawing, forming part thereof.

The figure is a top perspective view of a game board, showing my new design.

I claim:

The ornamental design for a game board, as shown.

FREEMAN R. STEARNS.
